GAME DEVICE

Harry A. Rubens, Joliet, and Edward R. Toerpe,
Galesburg, Ill.

Application March 26, 1938, Serial No. 198,190

3 Claims. (Cl. 273—140)

This invention relates to a game and more particularly to a novel and improved game wherein a number of elements are detachably mounted in a rack or the like, each of said elements having provided thereon an eye by means of which the said element may be hooked with a hook and line and by proper manipulation of the line after the element has been hooked, the same may be removed from the rack within which it is mounted.

It is the main object of this invention to provide a game of the character described, which employs the use of a hook and line, by means of which one of a series of elements may be hooked and then removed from its rack by the proper manipulation of the line, said elements being mounted in their respective racks in such a manner as to require the exercise of considerable skill in removing the same after the element has been hooked by the player.

Another object of this invention is to provide in a game of this character a plurality of detachably mounted elements in racks with means co-operating between said elements and the said racks for locking said elements to said racks, said elements being capable of removal from the racks only by the exercise of considerable skill, and fastening means for each of said elements to its respective rack being arranged so as to render the removal of said elements in some cases more difficult than others, and those elements which are the most difficult to remove being assigned a higher value than those which may be removed with greater ease, thereby producing a game which will not only be highly entertaining, but will also require the exercise of skill.

A further object of this invention is to provide in a game of the character described a hollow container having a plurality of slots provided in its upper face, through which may extend a plurality of elements, the shape of each of said elements representing a fish, and each of said elements having a depending portion extending into said container for engagement with pins or rods for fastening said elements in operative position in said container, the engagement between the elements and the pins or rods being such as to permit the removal of said elements from said container by proper manipulation of the element, and each of said elements being provided with an eye adjacent its upper portion adapted for engagement by a hook carried by a line, such as a fishing line or the like, whereby in the operation of this game the player or

players will attempt to hook one of the elements with the hook and line and after having hooked one of said elements will, with the use of the proper manipulation, attempt to remove said element from the container in which it is mounted.

A still further object of this invention is to provide a game of the character described, which will be simple in construction, assembly and operation, which may be produced along lines convenient for low-cost manufacture, and which will at the same time be highly amusing and entertaining, and will require the exercise of considerable skill for the proper manipulation thereof.

With the foregoing and other objects in view, which will appear as the description proceeds, the invention consists in certain novel features of construction, arrangement and combination of parts hereinafter fully described, illustrated in the accompanying drawing, and particularly pointed out in the appended claims, it being understood that various changes in the form, proportion, size and minor details of the structure may be made without departing from the spirit or sacrificing any of the advantages of the invention.

For the purpose of facilitating an understanding of our invention, we have illustrated in the accompanying drawing, a preferred embodiment thereof, from an inspection of which, when considered in connection with the following description, our invention, its mode of construction, assembly and operation, and many of its advantages should be readily understood and appreciated.

Referring to the drawing in which the same characters of reference are employed to indicate corresponding or similar parts throughout the several figures of the drawing:

Fig. 1 is a view in perspective of a game device embodying the present invention;

Fig. 2 is a top plan view thereof with parts thereof being broken away;

Fig. 3 is a side elevational view thereof with parts thereof being broken away to show the inner construction.

Referring to the drawing more specifically by characters of reference, the numeral 10 designates generally a box-like hollow structure having a top wall 11 and side walls 12. Provided in the top wall 11 are a plurality of rows or slots of elongated openings 13, said openings being arranged, as shown in the drawing, in longitudinal and transverse rows. Disposed within each of said slots or openings 13 is an element 14, said element being constructed so as to simulate the appearance of a fish or the like. To more fully

carry out the idea of the game, the upper wall 11 may have the proper ornamentation provided thereon to simulate a pool of water or a pond. This ornamentation is not shown in the drawing.

5 Each of the elements 14 is provided with a depending portion 15, which portion may be formed integral with the body of the element and is adapted for passing through the slot or opening 13 for disposition within the interior of 10 the member 10. The elements 14 may be constructed of any suitable material such, for example, as cardboard or the like, and the same may have the proper ornamentation provided thereon to present the appearance of fish or 15 the like.

Each of the depending portions 15 formed on the elements 14 is provided with suitable means for engagement by a pair of transversely disposed rods or pins 16, which pins or rods have their 20 ends supported in the side walls 12 of the member 10, there being one pair of said pins or rods 16 for each transverse row of elements 14.

As shown more clearly in Fig. 3, the means whereby the elements 14 are caused to engage 25 with the pins or rods 16 vary for different elements, thereby varying the ease with which said elements may be caused to disengage from its associated pins or rods. In the embodiment illustrated, the means provided on the elements for 30 engagement with said rods comprise a series of notches or cut-out portions provided in the depending portions 15, said notches or cut-out portions being designated by the reference character 17 and are adapted for engagement with the body 35 of the pins or rods for maintaining said elements in proper operative position in the member 10. By changing the shape of said cut-out portion 17, it will be apparent that the elements may be connected with their respective rods so as to 40 make it more difficult to remove some of said elements than others. By assigning different values to the various elements a very interesting and amusing game is produced.

The game is adapted to be operated or played 45 by players using a hook 21 and line 20, similar to a fishing line, and by the proper manipulation of said line, the said elements may be hooked by means of an eye 18 provided adjacent the upper edge of each of said elements.

50 The object of the game is to attempt to hook the elements bearing the higher numerical designations with the line, and then manipulating said line in such a manner as to bring about a disengagement between the element hooked and its associated pins or rods 16. By reason of the different 55 means employed for bringing about the engagement of the elements with their associated rods, it will be apparent that it will be easier to remove some of said elements than others, depending upon the nature of the engagement between a particular element and its associated rods.

From the above, it should be apparent that we have provided a game which will be highly 65 amusing and entertaining, and which will also require the exercise of considerable skill in the successful operation thereof. It will also be noted that the game may be assembled along lines convenient for low-cost manufacture. It will also be noted that the game may be highly edu-

tional, as the elements may be constructed to simulate various forms of fish or the like, thereby being very helpful in aiding children and others to learn the names of various types of fish, etc.

It is believed that our invention, its mode of 5 construction and assembly, and many of its advantages should be readily understood from the foregoing without further description, and it should also be manifest that while a preferred embodiment of the invention has been shown 10 and described for illustrative purposes, the structural details are nevertheless capable of wide variation within the purview of our invention as defined in the appended claims.

We claim:—

1. In a game of the character described, the combination of a hollow box-like structure having a top wall provided with a plurality of rows of elongated slots, each slot in any row being separated from and out of communication with 20 adjacent slots in said row, an element disposed within each of said slots and having a depending portion extending within said hollow member, means mounted within said hollow member for engagement with said depending portions for 25 detachably maintaining said elements in operative position, and means provided on said elements adapted for engagement by a hook and line, whereby the manipulation of said line may bring about a disengagement of said elements from 30 their engaging means within said container.

2. In a game of the character described, the combination of a hollow box-like container having a top wall provided with rows of slots, each slot in any row being separate from and out of 35 communication with adjacent slots in said row, an element disposed within each of said slots and having its body portion arranged about the top wall of the container and a depending portion extending within the container, means provided within said container for cooperating with 40 said depending portion for bringing about a detachable engagement between said element and said last-mentioned means for maintaining said 45 elements in operative position, means carried by each of said elements adapted for engagement by a hook having a line attached thereto, whereby the proper manipulation of said line may effect a disengagement of the element from its engaging means within the container.

3. In a game of the character described, the combination of a hollow box-like container having a top wall and side walls, a plurality of elongated slots provided in said top wall and arranged in horizontal rows, a plurality of pairs of rods disposed within said hollow member, there being one of said pairs of rods for each of said horizontal rows of slots, an element disposed within each of said slots and having its upper portion extending above said top wall and its bottom portion provided with means for detachable engagement with the aforementioned rods, means provided on each of said elements adapted for engagement by a hook attached to a line, said engagement between said elements and their associated rods being such as to permit the release thereof upon the proper manipulation of the line once an element has been hooked.
